UNITED STATES PATENT OFFICE.

DOMENICO GARGARO, OF DETROIT, MICHIGAN.

FORM FOR CASTING CONCRETE SEWERS OR THE LIKE.

Application filed September 16, 1925. Serial No. 56,608.

It is the primary object of my invention to provide a form to be used in casting concrete sewers or other like constructions, which form can be used in either open cut or tunnel work, and which shall be so constructed as to permit of easy and quick assembly and disassembly and which shall not waste concrete by permitting the same to flow through the form, as well as one which may be used to cast various sized sewers or the like.

With the above and other objects in view, my invention consists in the arrangement, combination and construction of the various parts of my improved device, as described in the specification, claimed in my claims and shown in the accompanying drawings, in which:

Fig. 1 is a side elevation showing one unit of my improved form with certain portions thereof cut away.

Fig. 2 is a sectional view taken on line 2—2 of Fig. 1.

Fig. 3 is a longitudinal, sectional, detailed view, showing my invention as applied at the joinder of two sections of my improved form.

I have shown my improved device as consisting of a base plate 5 having vertically extending lugs 6 at either end thereof, said lugs being provided with apertures 7 therein.

The base plate 5 is curved, as more particularly shown in Fig. 2, and a plurality of side plates 8 are assembled upon the base plate to form the greater portion of a tubular form. One of the longitudinal edges of each of the plates 8 is provided with inner strips 9 riveted, or otherwise secured to the plates, as at 10, and exterior lugs 11 riveted or otherwise secured to the plates, as at 12. The strips 9 and lugs 11 overlap the edges of the plates adjacent which they are attached and engage, in the case of those plates 8, which are adjacent the base plate 5, the longitudinal edges of the base plate 5 so as to effect a closed joint between the plates, and at the same time secure them together. This assembly leaves the top longitudinal edges of the plates 8, which are adjacent the base plate 5, unobstructed, and additional plates 8 are secured thereto by strips 9 and lugs 11, in the same manner as the plates 8 are secured to the base plate 5.

As many of the plates 8 as may be neces-

sary are used to build up the tubular formation of the form and any opening between the adjacent edges of the top plates 8 is covered by a curved plate 13.

Hoops 14 are disposed within the tubular formation made by the plates 5, 8 and 13, in order to support them, such hoops being constructed in two halves, the abutting edges of which are formed with lugs 15 secured together by bolts 16. Spacing members 17 are provided between the lugs 15 so that after the concrete formation has been made around the tubular form, the form may be taken apart by releasing the bolt 16, and removing the spacing members 17, so as to permit the two piece hoop 14 to collapse.

For the joining together of two or more sections of similar forms, the plates 8 are provided with lugs 18 similar to the lugs 6 having apertures 19 therein similar to the apertures 7 in the lugs 6. Thus when two sections of the form are placed end to end, the lugs 6 of the base plates of the two sections will abut, as will also the lugs 18 on the plates 8 of the two sections. Pins 20 are then inserted through the aligned openings 7 and the aligned openings 19 to join the two sections together.

It will be apparent, therefore, that my improved form may be used with equal advantage in open cut and tunnel work, that as many sections as are desired may be used and that the various sections may be assembled and disassembled with ease and facility.

It will further be apparent that various sizes of sewers or other like objects to be cast may be made from the same forms inasmuch as the curvature of the plates 8 may be varied by springing them inwardly or outwardly, and it will only be necessary that different sized plates 13 be used in order to cover the top openings left between the plates 8, which are on the top of the forms.

It will be apparent that various changes may be made in the arrangement, combination and construction of the various parts of my improved device without departing from the spirit of my invention, and it is my intention to cover by my claims such changes as may be reasonably included within the scope thereof.

What I claim is:

1. A form of the class described composed of a plurality of horizontally extending and

- transversely curved plates disposed to provide a tubular construction, hoops within said plates supporting same with a portion of the width of said hoops extending beyond the ends of said plates, other horizontally extending and transversely curved plates positioned with the ends thereof meeting the ends of the other plates over the extending portions of said hoops, lugs positioned adjacent the hoops on certain of the plates, and pins carried by at least two of the lugs over the inner face of said hoop, thereby fastening the horizontally extending sections of said form together.
- 15 2. In combination, a plurality of hoops, a horizontally extending and transversely

curved base plate extending under said hoops, horizontally extending and transversely curved side plates built up from the base plate on each side of said hoops, each of the said side plates having strips on the inside and outside of the lower edges thereof, only, fitting over the edge of the base or side plate contiguous thereto, and so forming sealed joints between said plates, and a horizontally extending and transversely curved top plate overlaying the top edges of the upper side plates to complete the tubular form by covering such opening as may remain between the upper edges of said upper side plates.

DOMENICO GARGARO.
